(57) **CLAIM**

The ornamental design for a garden marker, as shown and described.

DESCRIPTION

FIG. 1 is a perspective view of a garden marker in accordance with the present invention illustrating the front, top and left sides of the garden marker;

FIG. 2 is a back view of the garden marker of FIG. 1;

FIG. 3 is a front view of the garden marker of FIG. 1;

FIG. 4 is a left side view of the garden marker of FIG. 1; the

right side view being a mirror image of the left side;

FIG. 5 is a top view of the garden marker of FIG. 1;

FIG. 6 is a bottom view of the garden marker of FIG. 1;

FIG. 7 is a perspective view of the retaining sleeve illustrating the front, top and left sides of the sleeve shown removed from the staked holder for clarity of illustration;

FIG. 8 is a front view of the retaining sleeve of FIG. 7; the

back view being the same as the front view;

FIG. 9 is a left side view of the retaining sleeve of FIG. 7;

the right side view being a mirror image of the left side;

FIG. 10 is a top view of the retaining sleeve of FIG. 7;

FIG. 11 is a bottom view of the retaining sleeve of FIG. 7;

FIG. 12 is a perspective view of the staked holder without

the retaining sleeve being positioned therein; and,

FIG. 13 is a perspective view of the staked holder with the

retaining sleeve partially positioned therein.
